UNITED STATES PATENT OFFICE.

FRANCIS MURPHY, OF CHICAGO, ILLINOIS.

VENTILATING APPARATUS.

SPECIFICATION forming part of Letters Patent No. 381,078, dated April 10, 1888.

Application filed May 7, 1887. Serial No. 227,401. (No model.)

To all whom it may concern:

Be it known that I, FRANCIS MURPHY, a citizen of the United States, residing at Chicago, in the county of Cook and State of Illinois, 5 have invented certain new and useful Improvements in Ventilating Apparatus, of which the following is a specification.

This invention relates to an improvement in ventilators particularly adapted for use in 10 mines wherein it is desirable at times to force a current of air down through a shaft of the mine, and at other times to exhaust from the mine by inducing a current of air up through the shaft. An illustration of an apparatus for 15 such purpose may be found in a ventilator secured to me by Letters Patent of the United States No. 176,756, and involving in its construction the presence of a couple of rotary fan-wheels in connection with three stationary 20 chambers, whereof the middle one of the three chambers may be said to constitute the receiving-chamber, from whence air is supplied to the two stationary fan-wheel chambers in either forcing or exhausting. In my said apparatus 25 the chambers are provided with certain doors, whereby for forcing air into a mine the doors can be set to admit air from without into the receiving-chamber, and from thence to direct the current into and downwardly through the 30 side fan-wheel chambers to the shaft. On the other hand, to exhaust from the mine the doors can be set to direct the current from the shaft upwardly into the receiving-chamber, thence into the side fan-wheel chambers, and thence 35 out into the open air. During both of said operations the two fan-wheels are caused to revolve in one and the same direction, the reversal of the direction of the current being due to the adjustment of the several doors. The 40 presence of two fan-wheels in such apparatus has been rendered necessary in order to balance each wheel as against lateral pressure, and to such end the two fan-wheels are secured upon a rotary shaft common to both.

45 Prominent objects of my invention are to provide means whereby the direction of the current can be changed at will with greater facility than heretofore; to dispense with the necessity for two fan-wheels and to render the 50 employment of a single fan-wheel practical and efficient as a means for both forcing and ex-

hausting or for creating a current alternately in opposite directions; to dispense with the employment of a multiplicity of doors or gates and means for operating the same, and in general to simplify the construction of the apparatus; to adapt the apparatus for ready application either at the mouth of the pit or shaft or at any desired point along any of the galleries or passages through a mine or the like; 60 to insure the true and ready working of the apparatus under all circumstances, and to provide certain novel and improved details, all tending to promote the general efficiency of the apparatus.

65 To the attainment of the foregoing and other useful ends my invention consists in matters hereinafter described, and particularly pointed out in the claims.

In carrying out the principles of my invention I inclose a suitable fan-wheel within a reversible or rotary adjustable casing which can be swung about the axis of the fan-wheel so as to bring the discharge mouth or outlet of such fan-wheel casing into position to discharge 70 alternately in opposite directions. In this way, should the ventilating apparatus be placed at the mouth of a shaft or pit, the fan-wheel casing can be set either for forcing air down through the shaft or for exhausting from the 75 same, or, should the apparatus be located at one end of or at any point within a tunnel or other passage, the fan-wheel casing can be set for creating a current of air in either direction through such tunnel or passage, while, irrespective of the adjustment of the fan-wheel 80 casing and the direction in which its mouth is pointed to discharge, the fan-wheel itself can be driven either continuously or at desired 85 times in one and the same direction. I also provide means whereby when the fan-wheel casing is adjusted for creating a current in either of the two directions through the passage of a shaft, tunnel, or the like the transverse area of such passage shall at the point 90 of discharge from the fan-wheel casing be in effect temporarily contracted to the area of the discharge mouth or opening of the fan-wheel casing, in which way, while the fan-wheel casing can discharge at one side of such 95 point, it can take in air from the opposite side of the same. As a simple and efficient con-

struction for the attainment of such end, the fan-wheel casing can be mounted within a receiving-chamber open at both ends or at opposite points, and formed within a suitable casing which can be set either at the entrance to or at any point within the passage of a shaft, tunnel, or the like, whereby such chamber serves either as an extension of such passage or as a portion of the same. Under such arrangement the fan-wheel can be adjusted to discharge from either end of the receiving-chamber whereof the end at which such discharge is to take place can be temporarily contracted in area to the area of the discharge-mouth of the fan-wheel casing, leaving, however, the opposite end of the receiving-chamber open, so as to supply air to the fan-wheel. This temporary contraction of the receiving-chamber alternately at opposite ends can be attained by providing around the discharge-mouth of the fan-wheel casing a flange or ledge, which, when the fan-wheel casing is adjusted to discharge from either end of the receiving-chamber, will entirely close the space between the sides of the receiving-chamber and the fan-wheel casing at a point adjacent to the discharge-mouth of the latter.

Other matters of construction herein involved and tending to the general efficiency of ventilating apparatus will be hereinafter set forth.

In the drawings, Figure 1 represents in isometric perspective my improved apparatus applied for service in connection with the shaft of a mine. Fig. 2 is an enlarged detail representing a bearing for and one of the hollow hubs or journals of the fan-wheel casing, with the axle of the fan-wheel in cross-section. Fig. 3 represents the apparatus in side elevation with a portion of the outer casing broken away, the fan-wheel casing being set for forcing air down through the shaft of a mine. Fig. 4 is a sectional elevation taken on a plane coincident with the plane of the elevation in the preceding figure. In this view the fan-wheel casing is set for exhausting from the mine. Fig. 5 is a horizontal section on a plane indicated by the line $x-x$, Fig. 3. Fig. 6 is a vertical central section taken through Fig. 4 on a plane indicated by the line $y-y$.

In said drawings, A indicates the fan-wheel, and B the adjustable or reversible fan-wheel casing, which serves to provide a chamber for the fan-wheel. The adjustable fan-wheel casing is provided with the two oppositely-arranged air-inlet openings b and b' , and with an enlarged mouth or discharge-opening, as at b' . The inlet-openings b are arranged, respectively, at opposite sides of the casing at points to provide passages about the axis of the fan-wheel, while the discharge-opening b' is arranged to permit a large volume of air to be thrown from the fan-wheel directly out from the casing.

The preferred form of casing is proximately that of a half-elliptic-shaped drum, open at its largest end, which thus forms an expanded

mouth. The casing is hung to turn about the axis of the fan-wheel, which said axis is desirably at one side of the middle point of the 70 casing, thereby locating the fan-wheel somewhat eccentric to the curved wall of its enclosing-chamber, as best shown in Fig. 4, wherein it will be seen that, by reason of such relative disposition of the fan-wheel and casing, the space b^2 of the fan-wheel chamber, which is unoccupied by the fan, contracts toward one end and expands toward its opposite end. The contracted end of this space b^2 commences at the point where the air is first 8c thrown off from the fan-wheel, from which point the said space gradually expands to the enlarged discharge-mouth of the casing. It will also be seen that between said point of contraction and the mouth of the casing the 85 curved portion b^3 , Fig. 4, of the peripheral wall of the fan-wheel chamber lies in a curve, which from the point where the air is first thrown off from the fan-wheel runs off tangential to the fan-wheel. By such preferred 90 arrangement a large volume of air can without impediment be thrown off from the fan-wheel and out from the fan-wheel casing, as indicated by the arrows in Fig. 4.

The fan-wheel casing B is susceptible of rotary adjustment within a stationary receiving-chamber, C, which is open at both ends, as at c and c' , whereby the exit or discharge opening of the adjustable fan-wheel casing can be brought into position for discharging out from either of the two open ends of the receiving-chamber.

The adjustable fan-wheel casing is made somewhat smaller than the area of the receiving-chamber C in order to provide within the latter ample space for the reception of air and for supplying the same to the side inlets of the fan-wheel casing. The fan-wheel casing is, however, adapted to close the receiving-chamber at its two ends or mouths alternately, the 105 end of the receiving-chamber closed by the fan-wheel casing being dependent upon the position of the latter for discharging. Thus when the fan-wheel casing is in position for discharging from one end of the receiving-chamber 110 the latter will be otherwise closed at said end and its opposite end opened to admit air to the fan-wheel. A reversal of the fan-wheel casing will, however, reverse the order of the foregoing conditions. To the attainment of such end the fan-wheel casing is provided with a broad flange or ledge, D, surrounding the fan-wheel casing at a point adjacent to the discharge mouth or opening b' thereof, which said flange, when the fan-wheel 115 casing is at either of its two extreme positions, respectively illustrated by Figs. 3 and 4, serves to close the receiving-chamber at one end—that is to say, to close at one end of the receiving-chamber the space intervening between the walls of the receiving-chamber and the fan-wheel casing. The flange D is thus in effect a shifting gate or diaphragm capable of alternately closing the receiving-chamber 120

at opposite ends, but provided with an opening substantially corresponding with the outlet of the fan-wheel casing. By such arrangement, when the fan-wheel casing has been 5 thrown into either one of its two extreme positions it will be in position to discharge from one of the two ends of the receiving-chamber, which latter will be closed at one end, but open at its opposite end for receiving air and con- 10 ducting the same to the fan-wheel. This is clearly illustrated by Figs. 3 and 4, wherein the two positions of the fan-wheel casing are shown. In said figures the stationary casing of the receiving-chamber is shown arranged 15 over a short lateral extension or side passage, E, of the upper portion of the shaft E' of a mine, the open ends e of the receiving-chamber forming in such case, respectively, the top and bottom ends of the receiving-chamber.

20 In Fig. 3 the apparatus is in condition for forcing air into the mine, the adjustable fan-wheel casing being set to receive air from the top end of the receiving-chamber and to discharge at the bottom of the latter. In such 25 case the flange or ledge D will be in position to close the receiving-chamber at the bottom, and hence to leave the top of said chamber open.

In Fig. 4 the apparatus is set for exhausting from the mine, the fan-wheel casing being 30 shown reversed in position and ready for discharging out from the top end of the receiving-chamber, which latter is now closed at said top end by the flange or diaphragm D.

Under both of the two foregoing conditions 35 the fan-wheel will be driven in one and the same direction from an engine or suitable motor stationed at any desired point.

The fan-wheel casing is hung or mounted so 40 as to turn or swing independently of the axle of the fan-wheel, but about the axis thereof, whereby the fan-wheel casing can be freely turned so as to reverse the position of its discharge-outlet without interfering with the fan-wheel, and at the same time the proper relative 45 relationship between the fan-wheel casing and the fan-wheel will be preserved irrespectively of the position of the said casing.

As a means for mounting the fan-wheel casing it is provided with a couple of hollow hubs 50 or journals, F, respectively located at opposite sides of the same and rigidly connected with the fan-wheel casing by arms F', arranged to radiate from the hollow hubs to an extent to span the inlet-openings b of the fan-wheel 55 casing and permit the securement of their outer end to the side of such casing at intervals around the inlet-openings thereof. These arms may be secured to the hollow hubs, but are more desirably cast integral therewith.

60 The hollow hubs or journals F of the fan-wheel casing are supported to turn in bearings G, which may be formed as bracket-bearings and secured within and at opposite sides of the stationary receiving-chamber either to 65 the side walls thereof or to any suitable fixture.

The rotary shaft or axle A', whereon the fan-

wheel is secured, extends centrally through the hollow hubs or journals F of the fan-wheel casing, but is free from bearing or frictional contact with said hubs or journals, in which way the journals of the fan-wheel casing can turn freely and independently of the fan-wheel axle, which latter will of course be in no wise affected by any rotary adjustment on the part 75 of the fan-wheel casing.

The bearings H for the axle of the fan-wheel are separate and independent from the bearings for the fan-wheel casing and may be conveniently arranged outside of the outer stationery casing of the receiving-chamber.

To insure the steady and uniform running of the fan-wheel under all circumstances and to avoid undue binding upon or cramping of the axle, should, for example, any portion of 85 the outer frame or casing sag by reason of a giving away of the earth or other supporting media, the bearings for the said axle are in the nature of rocking or universal bearings. To such end the blocks or bearings h, Fig. 6, 90 through which the axle passes, are externally rounded and held within bearings or seats h', which are internally concaved in correspondence with the rounded bearings h, thereby providing rocking or universal joints between the 95 two, which will render the bearings self-adjusting with reference to such inclination as the axle might be caused to assume.

The flange or ledge D around the discharge-mouth of the fan-wheel casing will be properly secured to the latter and suitably braced— 100 as, for example, by braces D', disposed at desired points.

As herein shown, the diaphragm or ledge D is beveled at its opposite end edges, which beveled edges are adapted to match the correspondingly-beveled faces of certain portions of the casing of the receiving-chambers when the fan-wheel casing is at either of its two extreme positions. Thus, for example, when the 110 fan-wheel casing is in position for exhausting from the shaft or tunnel, as in Fig. 4, one beveled edge of the ledge or diaphragm will enter and fit a beveled groove, c', in one side wall of the casing of the receiving chamber C, while 115 the opposite beveled edge of the ledge or diaphragm will fit against a like beveled edge of a ledge, c'', fixed within and to the said outer stationary casing.

The construction and arrangement of the 120 wings or blades of the fan-wheel herein shown are substantially the same as in my patent hereinbefore referred to.

While I do not limit myself to the construction of fan-wheel employed, the construction 125 set forth in my said patent will be found desirable and exceedingly effective.

The fan-wheel is strengthened and its peripheral ring or rim supported by radial arms a, which connect the rim portion with hubs or 130 collars fixed upon the axle A'. These radial arms have their surfaces set obliquely to the plane of the fan-wheel, in order to assist during the rotation of the latter in drawing air

through the opening in the fan-wheel casing and into the wheel. An annular flange, d^2 , is also desirably applied to each side of the fan-wheel or to the fan-wheel casing, and each arranged as a guard to close any space between the edge of the circular opening b in the fan-wheel casing and a similar opening in the fan-wheel.

Since the reversible or adjustable fan-casing is provided with inlet-openings at opposite sides of the fan-wheel, the latter will balance as against pressure during operation, and hence but one fan be rendered necessary for forcing air into a mine or through a tunnel and 15 for exhausting from the same.

In the several figures of the drawings the apparatus is represented as applied for forcing the air down into a mine and for exhausting air therefrom, to which end the heavy framework K, for supporting the casing c of the air-receiving chamber, can be laid upon the ground; but it will be obvious that the apparatus could be applied at any point along a passage within the mine, or at the entrance to or other point 25 within a tunnel or other passage wherein it may be desirable to induce a current of air alternately in opposite directions.

In conclusion, it may be stated that with regard to the hereinbefore-described feature of the fan-wheel casing capable of rotary adjustment about the axis of the fan-wheel and provided with hollow journals through which the axle of the fan-wheel is extended, with said fan-wheel casing supported upon bearings independently of the bearings for the fan-wheel axle or journals, said feature is herein understood to be applicable in other connections—such, for example, as set forth in applications for Letters Patent of the United States heretofore filed by me, and serially numbered 26,464 and 83,592.

What I claim as my invention is—

1. In a ventilating apparatus, the combination, with a rotary fan-wheel, of the reversible fan-wheel casing inclosing the fan-wheel, and a chamber open at oppositely-disposed points and constituting a passage wherein the fan-wheel casing is mounted and capable of adjustment for directing a current either way through the said chamber, substantially as described. 50

2. In a ventilating apparatus, the combination, with the receiving-chamber open at opposite points, of a fan-wheel, and the reversible fan-wheel casing provided with a flange or ledge, D, and mounted within the receiving-chamber to turn about the axis of the fan-wheel, said ledge of the fan-wheel casing being adapted to close the space between the sides of the receiving-chamber and the fan-wheel casing when the latter is in position to discharge from either of the oppositely-arranged openings of the receiving-chamber, substantially as described. 60

3. The combination, substantially as hereinbefore set forth, with the fan-wheel casing capable of rotary adjustment about the axis of the fan-wheel and provided with hollow journals, of the fan-wheel having its axle extending through the hollow journals of the fan-wheel casing, the said journals of the fan-wheel casing being supported upon bearings independent of the bearings for the fan-wheel axle, substantially as set forth. 70

4. In a ventilating apparatus, the combination, with the rotary adjustable fan-wheel casing, of the fan-wheel having its axle independent of the fan-wheel casing and mounted upon separate rocking bearings, substantially as described. 75

FRANCIS MURPHY.
